UNITED STATES PATENT OFFICE.

GEORGE A. BROOKE, JR., OF GERMANTOWN, PENNSYLVANIA.

AUTOMATIC PRESSURE CONTROL.

Application filed August 4, 1921. Serial No. 489,916.

To all whom it may concern:

Be it known that I, GEORGE A. BROOKE, Jr., a citizen of the United States, residing at Germantown, in the county of Philadelphia, State of Pennsylvania, have invented a new and useful Automatic Pressure Control, of which the following is a specification.

The invention relates to automatic pressure control. The invention is especially applicable to combustion control. The object, in which case, being to control automatically the combustion, by utilizing the pressure in the combustion chamber to regulate or control automatically, for example, damper, or draft. The invention is especially applicable for regulating the inlet of air which passes through the fuel bed.

The invention comprises improvements in pressure responsive devices and the method of operating the same.

Referring to the drawings which illustrate merely by way of example suitable means for effecting my invention:

Fig. 1 is a section on line 1, 1 of Fig. 2.

Fig. 2 is a section on line 2, 2 of Fig. 1.

Fig. 3 is an elevation, partly broken away, showing the buoyant elements in different positions.

Similar numerals refer to similar parts throughout the several views.

In these drawings I have shown the chambered body 9 forming a receptacle for liquid. From the top or cover 10 a partition or apron 11 projects downwardly to near the bottom of the chamber, so as to dip into the liquid contained therein. The partition 11 thus forms a liquid sealed partition between the compartments 12 and 13. Beneath the chambered body 9 is provided a channel forming body 14, having a channel or passage 15 provided with a port as at 16 for connection with a conductor 17 leading from the combustion chamber or space or region 18 from which the pressure to be utilized is derived.

To one end of channel 15 is connected the upwardly extending pipe 18 open at the top within compartment 12 and within the buoyant element 21. To the other end of channel 15 is connected the upwardly extending pipe or conductor 19 open at the top, within compartment 13, outside the buoyant element. Another pipe 20 extends upwardly through the bottom of compartment 13, open at the top within the buoyant element 22,

and at the bottom communicating with atmosphere. Within the chambered body 9 is provided the balanced buoyant structure comprising the bells or buoyant elements 21 and 22 rigidly secured together by the curved connecting frame 23, extending at its middle portion beneath the lower edge of partition 11, and consequently beneath the level of the liquid contained in the chamber. 60 65

It will thus be seen that the gas pressure through pipe 18 is delivered beneath the element 21, while the space in compartment 12, about and above element 21, is open to atmosphere by means of openings 26. 70

The gas pressure through pipe 19 is delivered into compartment 13, about element 22. This compartment 13 is not in communication with atmospheric pressure.

Pipe 20 which extends upwardly through the bottom of compartment 13, maintains the space within element 22, above the level of the liquid, in communication with atmosphere. In other words the gas pressure is beneath element 21 while atmospheric pressure is above it in compartment 12, while atmospheric pressure is beneath element 22 while gas pressure is above it, in compartment 13. The result is that said change of pressure is directly effective with respect to 80 85 each of a pair of buoyant elements, secured together and pivotally mounted in opposite directions on each side of their axis of movement, but in the same direction of their rotative movement. 90

To the connecting frame 23 is secured the supporting shaft member 24, journaled preferably on pivot points in bearings 25, at each end of the shaft.

This shaft 24 extends through openings 26 in the walls of compartment 12. To shaft 24 is secured the controlling lever 27.

Merely by way of example this lever 27, as indicated, is connected in an electric circuit and is adapted to cooperate with the 100 electrical contacts 28 and 29; that is to say, when actuated by the buoyant structure, to engage with one or the other of said contacts. This results in the closing of one or the other of two electric circuits. The closing of one circuit causes the operation of a motor in one direction, and the closing of the other circuit causes said operation in the opposite direction to actuate, for example a valve or damper or other pressure controlling device in a manner well known in the art. The details of such an arrangement 105 110

form no part of the present invention and are therefore not shown. This invention is confined to the improved method and means for utilizing the pressure derived from a given region to actuate any suitable controller, such for example the contact lever 27.

As means for adjustment, with respect to the change in pressure required to cause the actuation of the controller lever 27, the weights 27' and 27'' are provided, threaded on the lever 27 and adapted to be moved toward or away from the axis of said lever 27.

There is also provided an adjustable weight or counterbalance 31, threaded, or secured by the set-screw 32, or both, on the arm 33 fixed to the shaft member 24.

The weights 27' and 27'' are adjusted with respect to the pressure desired to be maintained.

The counterbalance 31 is adjusted to compensate in part for the change in buoyancy of the buoyant elements when moved from normal position by any change in pressure.

This weight 31 is normally held in neutral position. When pressure is exerted upon the buoyant elements, tending for example to lift element 12 out of the liquid, its buoyancy is reduced which tends to counteract the action of said exerted pressure, correspondingly as pressure is exerted on element 13, tending to cause its further immersion, its buoyancy increases, and thus it tends to react correspondingly against said pressure. This tendency of the elements to react against said exerted pressures is, to the required degree, counterbalanced by the weight 31. For example as the arm 33 is tilted out of the vertical, the weight 31, being properly adjusted, as it moved out of the said vertical or neutral position, exerts pressure upon the buoyant elements to compensate in part for their change in buoyancy, so that the desired length of stroke for any given change in pressure may be secured by said adjustment.

As long as the liquid is of sufficient level to maintain the seal with the elements, its change in level affects oppositely but equally the buoyancy of each of both elements, so that such change or variation of liquid level does not impair the balance or adjustment of the device.

In operation:

It will be obvious, from the above description, that when there is an abnormal pressure in the region desired to be controlled, the elements will respond, causing the movement of the controller in one direction to effect the pressure control as above indicated. When there is a subnormal pressure in said region the buoyant structure will be actuated to move the controller in the opposite direction.

What I claim is:—

1. The method of automatic pressure con-

trol, which consists in utilizing variations from normal of the pressure in a given region, acting directly, but in opposite directions, upon two connected pressure responsive devices to actuate a controller.

2. The method of automatic pressure control, which consists in utilizing variations from normal of the pressure in a given region, acting directly, but in the same rotative direction, upon each of two connected buoyant elements to actuate a controller.

3. The method of automatic pressure control which consists in utilizing variations from normal of the pressure in a given region, acting directly, but in opposite directions, upon two connected buoyant elements to actuate a controller, and utilizing a balancing force, becoming effective upon the movement of the buoyant elements, to compensate for variations in immersion.

4. The method of automatic pressure control, which consists in utilizing variations from normal of the pressure in a given region to cause the actuation of a pair of rigidly connected buoyant elements, said actuating pressure acting directly upon each buoyant element and cooperating with buoyancy as to one and in opposition to buoyancy as to the other buoyant element.

5. The method of automatic pressure control, which consists in utilizing variations from normal of the pressure in a given region, acting directly, but in opposite directions, upon two connected buoyant elements to actuate a controller, and utilizing a gravity actuated force, becoming effective upon movement from normal of the buoyant elements, to compensate in part for changes in buoyancy.

6. The method of automatic pressure control, which consists in utilizing variations from normal of the pressure in a given region, acting directly, but in opposite directions, upon two connected buoyant elements to actuate a controller, utilizing a gravity actuated force, becoming effective upon movement from normal of the buoyant elements, to compensate in part for changes in buoyancy, and utilizing and adjusting gravity actuated forces for determining the normal pressure to be maintained in said given region.

7. In an automatic pressure control, the combination of a pair of cooperating buoyant elements, and means for communicating directly to each element the pressure of a given region, said pressure exerted against buoyancy as to one element and with the buoyancy as to the other.

8. In an automatic pressure control, the combination of a pair of cooperating buoyant elements, means for communicating directly to each element the pressure of a given region, said pressure exerted against buoyancy as to one element and with the buoy-

ancy as to the other, and so that variations from normal of said pressure shall actuate said buoyant elements.

9. In an automatic pressure control, the combination of a pair of cooperating buoyant elements, means for communicating directly to each element the pressure of a given region, said pressure exerted against buoyancy as to one element and with the buoyancy as to the other, and so that variations from normal of said pressure shall actuate said buoyant elements, both in the same rotative direction.

10. In an automatic pressure control, the combination of a pair of cooperating pivotally mounted buoyant elements, and means for communicating directly to each element the pressure of a given region, said pressure exerted in the same rotative direction as to each buoyant element.

11. In an automatic pressure control, the combination of a pair of cooperating pivotally mounted buoyant elements, and means for communicating directly to each element the pressure of a given region, said pressure exerted in the same rotative direction as to each buoyant element, said elements being so shaped as to have a constant cooperative action, with variation of the liquid level.

12. In an automatic pressure control, the combination of a pair of cooperating buoyant elements, and means for communicating to each element the pressure of a given region, said pressure exerted against buoyancy as to one element and with the buoyancy as to the other, and a balancing device normally ineffective for compensating in part for change in buoyancy when said elements are actuated.

13. In an automatic pressure control, the combination of a pair of cooperating buoyant elements, and means for communicating

directly to each element the pressure of a given region, said pressure exerted against buoyancy as to one element and with the buoyancy as to the other, and so that variations from normal of said pressure shall actuate said buoyant elements, and adjustable devices for determining the pressure which shall be considered normal in said region.

14. In an automatic pressure control, the combination of a pair of cooperating buoyant elements and air gate, controller therefor, and means for communicating directly to both buoyant elements the pressure of a given region, so that variations from normal of said pressure shall actuate the buoyant elements and the controller.

15. In an automatic pressure control, the combination of a pair of cooperating buoyant elements, an air gate, a controller therefor, and means for communicating directly to both buoyant elements the pressure of a given region, so that variations from normal of said pressure shall actuate the buoyant elements and the controller, said buoyant elements having outer submergible walls in arcs of their axis of movement.

16. In an automatic controlling device, the combination of a liquid container, separated into two compartment by a liquid sealed partition, a buoyant device having an element operating in each compartment, means for communicating pressure from a given region to beneath one element and to above the other element, and adjustable means in connection with said buoyant device, for predetermining the normal pressure in said region, variations from which are to be effective in respect to the actuation of the buoyant device.

GEORGE A. BROOKE, JR.
